UNITED STATES PATENT OFFICE.

WILLIAM E. GRAY, OF CHICAGO, ILLINOIS, ASSIGNOR TO MOORE ELECTRIC CORPORATION, OF CHICAGO, ILLINOIS.

HAIR CLIPPER.

Application filed July 14, 1921. Serial No. 434,793.

To all whom it may concern:

Be it known that I, WILLIAM E. GRAY, a citizen of the United States, and a resident of the city of Chicago, county of Cook, and 5 State of Illinois, have invented certain new and useful Improvements in Hair Clippers, of which the following is a specification.

My invention relates to improvements in hair clippers and more particularly to the 10 means for retaining the cutting blade in position thereon, the object of the invention being to provide a simple effective construction for this purpose by means of which the cutting blade will be nicely and adjustably 15 held in place and the working parts protected.

Other objects will appear hereinafter.

The invention consists in the combinations 20 and arrangements of parts hereinafter described and claimed.

The invention will be best understood by reference to the accompanying drawings forming a part of this specification, and in which,

25 Fig. 1 is a side view, shown partially in section, of a hair clipper embodying the invention,

Fig. 2 is a section taken on line 2—2 of Fig. 1,

30 Fig. 3 is a partial top plan view of the construction, and

Fig. 4 is a section taken on line 4—4 of Fig. 1.

The preferred form of construction as 35 illustrated in the drawings comprises the usual serrated cutter head 5 having a suitable handle 6 rigidly attached thereto. The usual serrated cutting blade 7 is arranged to reciprocate on head 5 and co-operate 40 therewith in the usual manner. The cutter blade 7 is provided with two slots 8 loosely fitting over the upstanding guide posts 9 on the cutter head 5 for guiding said blade in its reciprocations.

45 A housing 10 is arranged on top of the blade 7, being provided with contact lugs 11, resting on top of said blade. The housing 10 is provided at its lower portion with a horizontal flange 12 having slots 13 there- 50 in, fitting snugly over the guide posts 9 and whereby the lower portion of the housing will be held nicely in place. The upper portion of the housing 10 is provided with a substantially semicircular socket 14 embrac- 55 ing the substantially semicircular end 15 of

an abutment 16 formed integrally with the handle 6 and overhanging the blade 7 as shown. A vertical set screw 17 is threaded in the abutment 16 passing downwardly therethrough and contacting with the horizontal flange 18 formed on the upper portion of the housing 10 and whereby the pressure between housing 10 and blade 7 may be nicely adjusted as desired. A coiled spring 19 is imprisoned between the head of 60 the screw 17 and the top of the abutment 16, exerting friction on said screw and yieldingly locking the same in various positions of adjustment.

The blade 7 is reciprocated by a lever 20 70 connected with any usual or desired form of driving shaft mechanism in the handle 6.

By this arrangement, housing 10 will be nicely and firmly held in position over the blade 7 and the operating contact between 75 said blade and the cutter head 5 readily adjustable by means of the screw 17.

While I have illustrated and described the preferred form of construction for carrying 80 my invention into effect, this is capable of variation and modification without departing from the spirit of the invention. I, therefore, do not wish to be limited to the precise details of construction set forth, but desire to avail myself of such variations and 85 modifications as come within the scope of the appended claims.

Having described my invention, what I claim as new and desire to secure by Letters Patent is:

1. A hair clipper comprising a cutting head; a cutting blade cooperating therewith; an abutment associated with said blade; a housing loosely engaging said blade and abutment; and means for pressing said housing into engagement with said blade, substantially as described.

2. A hair clipper comprising a cutting head; a cutting blade cooperating therewith; an abutment on said head above said blade; a housing resting on said blade and loosely embracing said abutment; and means on said abutment pressing said housing into engagement with said blade, substantially as described.

3. A hair clipper comprising a cutting head; a cutting blade cooperating therewith; an abutment on said head above said blade; a housing resting on said blade and loosely embracing said abutment; and an adjusting 110

screw carried by said abutment and pressing said housing into engagement with said blade, substantially as described.

4. A hair clipper comprising a cutting head; a reciprocating cutting blade on said head cooperating therewith; an abutment on said head above said blade; a housing resting on said blade and provided with a socket embracing said abutment; a set screw threaded in said abutment and passing downwardly therethrough; and a flange on said housing contacting with the lower end of said set screw, substantially as described.

5. A hair clipper comprising a cutting head; upstanding guide posts on said head; a reciprocating cutting blade cooperating with said head and having slots fitting over said posts; an abutment above said blade; a

housing resting on said blade and having slots in its lower portions engaging said posts and a socket in its upper portions embracing said abutment; a set screw threaded in said abutment and passing downwardly therethrough; a flange on said housing contacting with the lower end of said set screw; and a spring on said set screw between the head thereof and the top of said abutment, substantially as described.

In testimony whereof I have signed my name to this specification in the presence of two subscribing witnesses.

WILLIAM E. GRAY.
